UNITED STATES PATENT OFFICE.

ALLEN D. CARDWELL, OF ROCKVILLE CENTER, NEW YORK.

MEANS FOR MAKING ELECTRICAL COILS.

Application filed July 14, 1925. Serial No. 43,527.

In my application for Letters Patent for improvements in transformers and inductances, filed May 16, 1925, Serial No. 30,666, I have set forth various forms of coils of wire adapted for use in electrical instruments, such as in radio receiving sets, etc., wherein the turns of windings of the coil are secured together and spaced apart by means of longitudinally disposed binding cords and other cords looped across each of the turns of convolutions of the coil, located between adjacent turns, and looped around the longitudinal cords, forming a bind or tie at each turn.

The object of my invention is to provide an improved method of and means for producing coils of the character above set forth, whereby any desired number of longitudinal cords and corresponding binding cords may be associated with the turns or windings of the coil in a simple and accurate way, and whereby such turns or windings will be secured together in spaced relation providing coils not requiring cores to support them.

In carrying out my invention I wind a conductor, either bare or insulated, in turns or convolutions side by side, lay one or more longitudinally disposed cords adjacent to said turns or convolutions and loop a binding cord around the corresponding longitudinal cord and across turns or convolutions of the conductor in such a way that portions of the binding cord extend between adjacent turns or convolutions, whereby the turns or convolutions are secured together in spaced relation.

In the form of mechanism I have illustrated in the accompanying drawings I provide a mandrel and means to wind turns or convolutions of wire therearound, means to lay one or more longitudinal cords along the turns or convolutions as wound, and means to cause a looping cord to be passed around the longitudinal cord for turns of conductor and across the latter, either from the outside or from the inside thereof, and so on successively as the turns or convolutions of the conductor are laid around the mandrel.

My invention also comprises novel details of improvement that will be more fully hereinafter set forth and then pointed out in the claims.

Reference is to be had to the accompanying drawings forming a part hereof, wherein Fig. 1 is a side elevation of a machine adapted to carry out my invention;

Fig. 2 is an enlarged detail section on line 2, 2, in Fig. 1;

Fig. 3 is a detail of Fig. 2;

Fig. 4 is a detail plan view illustrating the assembly of parts for laying the longitudinal and binding cords in conjunction with wire turns, taken approximately along line 4, 4, in Fig. 1;

Fig. 5 is a detail view looking upwardly, substantially on line 5, 5, in Fig. 1;

Fig. 20 is a side view illustrating my improved coil; and

Fig. 21 is a side view of Fig. 20.

Similar numerals of reference indicate corresponding parts in the several views.

At 1 is a frame or support shown in the form of a ring which may be supported in any suitable manner, such as by legs 2 suitably attached to said frame. At 3 is a mandrel or form around which the conductor wire A, which may be insulated or bare, is adapted to be wound in suitable turns or convolutions, (Figs. 15 to 21), which mandrel is shown centrally disposed within frame or ring 1 and is preferably supported to depend within said ring, as illustrated in Figs. 1 and 6. The mandrel 3 is shown depending from a cross bar 5 supported upon

frame or ring 1, as by means of posts 6 secured on said frame or ring, so that the bar 5 projects from the frame and the mandrel depends in such a way that when the conductor A is wound along the lower portion of the mandrel the coil will advance downwardly from the mandrel and hang therefrom. By preference a portion of the mandrel is tapering at 3^a, (Fig. 6), so that as the conductor A is wound at the tapering portion the latter will serve to force the successive convolutions downwardly along the mandrel to feed the coil. It will be obvious that the mandrel may stand upright instead of depending, in which event the coil will be fed upwardly instead of downwardly. The conductor or wire A is carried on a spool 7 and is led from the spool to a guide tube 8, being shown guided to said tube from the spool by means of a pulley 9 and a stud 10, and through a tensioning device 10^a, (Figs. 6 and 7). The spool 7 is detachably carried by brackets 11. The parts 7, 8, 9, 10, 10^a and 11 are carried by a guiding ring 12 that is rotative within the inner guiding surface 1^a of frame or ring 1, so that the spool will be rotated around the mandrel to wind the conductor thereon. The guide ring 12 is shown rotatively supported in connection with the frame or ring 1 by means of upper and lower annular plates 13, 14 secured to said guide ring, as by screws 15, with the outer marginal portions of said annular plates opposing the adjacent edge portion of frame or ring 1, (Figs. 2 and 6). The guide ring 12 is provided with an annular gear 16 which may be secured thereto by the screws 15, which gear is shown below the annular plate 14 and may be rotated in any suitable way. I have shown a pinion 17 in mesh with gear 16 and carried by a shaft 18 journaled in bracket 19 hung from frame or ring 1, (Figs. 1 and 2). Shaft 18 is provided with a bevel gear 20 in mesh with a bevel gear 21 carried by shaft 22 journaled on bracket 19. Shaft 22 is shown provided with pulley 23 receiving a belt 24 which may be driven by a motor 25 supported by legs 2, (Fig. 1).

During the rotation of guide ring 12 the conductor A will be wound around the mandrel, the turns or convolutions of the conductor succeeding one another to produce the coil, such as illustrated in Fig. 20. At B, C are binding cords for securing the turns or convolutions of the coil together in spaced relation. I use the term "cord" in the specification and claims in a generic sense, intending it to mean ordinary cord or twine in round or other cross section, or a strip of tape or ribbon-like element of insulating material.

The cord B is laid to extend along the turns or windings of the coil, either outside of the same or within the coil, or partially

outside and partially within the coil, as illustrated in Fig. 21, and the cord C is used as a looping or binding cord. I have illustrated means for applying six longitudinal cords B in connection with the coil and six supplemental looping or binding cords C, and since the means I have illustrated for laying and looping the cords is the same for each pair B, C thereof the description of the mechanism for laying one set of cords B, C, will suffice for all, it being understood that such mechanisms are placed in suitable spaced relation around the mandrel so that the complementary or pairs of cords will be laid and looped in conjunction with the turns of the coil successively as the latter are wound around the mandrel.

The longitudinal cord B is supplied on a spool 32 whose spindle 33 is journaled in bracket 34 secured upon a ring or plate 35 supported by the legs 2 above the winding and cord laying mechanism, (Fig. 1). Bracket 34 is shown slotted at 34^a for detachable reception of spindle 33. The spindle is provided with a pulley 36, and a cone-nut 37 threaded on spindle 33 serves to detachably secure the spool to the spindle, (Fig. 13), by forcing the spool against the pulley. The cord B passes over a guide pulley 38 journaled overhead at the end of an arm 39 journaled at 40 upon bracket 34. A spring 41 connected with the arm and with bracket 34 serves to resiliently cause pulley 38 to rise to apply tension to cord B from the pulley to a guide 42 below, through which guide the cord passes for guiding it to the mandrel. At 43 is a cord passing around pulley 36 and connected at one end to bracket 34, at 44, and at the opposite end cord 43 is connected to a spring 45 that is connected at 46 to arm 39, (Fig. 12), whereby the cord 43 exerts frictional resistance of rotation to pulley 36 and thereby to the spool carrying the cord B. The guide 42 is pivotally supported upon frame or ring 1, at 42^a, in bracket 47 secured upon said frame, so that the free end of the guide may rock relatively to the mandrel, as up and down respecting the same, (Figs. 1 and 6). As a means for rocking guide 42 in timed relation to the rotation of the conductor-guide 8 around mandrel 3 I provide a cam-member or wall 48, upstanding from and secured to the ring plate 13, as by means of brackets 49, (Figs. 6 and 9). The cam-member 48 is of suitable length, the ends of said cam-member at 48^a being suitably curved downwardly toward plate 13 to travel under and raise the guides successively and to pass therefrom to permit the guides to descend successfully, the guides being preferably provided with rollers at 42^b to engage the upper edge of cam-member 48, (Fig. 6). A spring at 50 may be connected with the guide 42 and with frame or ring 1 tending normally

to depress the guide, and at 51 is a stop for the guide to limit its downward movement (Fig. 6).

The cord B, after leaving the delivery end 5 of guide 42, is located with relation to the mandrel 3, as indicated in Fig. 6, in such a way that each time that the guide 8 lays a turn of conductor A in appropriate position against the mandrel such portion of the 10 conductor will be in conjunction with the cord B which will pass longitudinally along the coil as made. At such point the binding or looping cord C is looped around the longitudinal cord B and partially around or 15 across the corresponding portion of the conductor turn. The cord C is carried on a spool 53 which is adapted to be rotated bodily around the cord B to loop the cord C therearound. The spindle of spool 20 53 is journaled in brackets 54 secured upon a rotative disk 55 that is journaled in an annular raceway 56^a in a head 56 that is secured to and depends from the frame or ring 1, (Fig. 9). The head 25 56 has a bracket or supporting portion 57 secured thereto by bars or bolts 58, whereby the parts 56 and 57 are secured together in spaced relation. The bracket 57 is secured to frame 1 by screws 59 passing through a 30 flange portion 60 of the bracket, which flange portion is preferably provided with arcuate slots 61 receiving said screws so that the bracket 57 and the head 56 may be adjusted angularly with respect to the mandrel, (Figs. 5 and 9). The disk 55 is provided with a ring gear 64 that is secured to said disk by screws 65 and rotates the disk, (Fig. 10). The raceway 56^a is formed between a surface 56^b on one side of head 56, 35 an annularly disposed bearing seat 56^c on said head and a ring-like plate 62 secured to said head by screws 63, (Fig. 10^a). The disk 55 rotates against the face 56^b, seat 56^c and plate 62, thereby rotatively supporting gear 64. The upper portion of plate 62 is 40 cut away at 62^a, (Fig. 10), and adjacent outer portions of the disk 55 and the ring gear 64 are also cut away or open at 66, (Fig. 11), so that when the parts are in the 45 position shown in Fig. 10 the cord B may be depressed into the interior of plate 62, disk 55 and the ring gear 64, by the downward movement of guide 42, to enable the spool to be rotated bodily around the said cord. 50 The disk 55 is shown provided with a hole 67 through which the cord C from spool 53 is guided to a tension device 68 carried by the disk, a guide eye 69 on the disk receiving the cord from the tension device, whence the cord passes through a bore 70^a in a 55 guide arm 70 secured on disk 55, (Figs. 9 and 11). The guide arm rotates with the disk and serves to lay the cord C around the cord B at certain times when the cord 60 B has been depressed into the opening in

disk 55. For rotating the disk 55 I journal upon the head 56 spaced pinions 71 both in mesh with gear 64, for spanning the space at 66 in said gear, (Fig. 10), said pinions being also in mesh with a drive gear 72 secured on shaft 73 journaled in bearings in head 56, (Fig. 9). The shaft 73 is provided with a bevel gear 74 in mesh with a drive gear 75 secured on a vertical shaft 76 journaled in bearings in bracket 57 of head 56, 70 and frame 1 and is provided with a gear 77 adapted to mesh with the gear 16 that is carried by ring 12, (Figs. 6 and 9). The teeth around the lower portion of gear 16 for a suitable distance are omitted, as indicated 75 at 16^a, and the teeth are continuous around the upper portion of the gear, (Fig. 8). The arrangement is such that when gear 77 engages teeth 16 the shaft 76 will be rotated, and thereby through the gearing 75, 74, 73, 80 72 and 71 the ring gear 64 will be given one complete rotation from the position shown in Fig. 10 where the spaces 62^a and 66 are in register with the space 56^a of head 56, at the time that the cord B has been 85 depressed through such spaces so that the spool 53 will carry the cord C around the cord B. Thereupon such teeth of gear 16 pass from gear 77 and the latter comes to rest with the spaces 62^a and 66 again in 90 register. During the period of rest the reduced smooth surface, at 16^a of gear 16, where the teeth are omitted, will oppose the gear 77 without rotating it, and at such time the concave reduced surface 78^a of disk 78 95 that is secured on shaft 76 will engage the annular surface 14^a of ring plate 14 to keep shaft 76 from rotating, and thereby to keep spool 53 from being bodily rotated, (Fig. 7). When the gear 77 engages the teeth 16 100 of gear 16 the annular surface of the disk 78 will rotate along a reduced annular edge portion 14^b of ring plate 14 so that the gear 77 may be rotated by gear 16. One inclined portion 14^c of ring plate 14 permits the reduced 105 surface 78^a of disk 78 to ride to one end of the surface 14^b and the other inclined surface at 14^c permits the reduced part 78^a of gear 78 to ride up on the annular portion 14^a 110 of the ring plate 14, (Fig. 7). By the means described the gear 77 is caused to rotate once for each complete rotation of gear 16 but only for a limited period of the last named rotation for timing the successive rotations of spool 53 bodily around the cord B. 115

In the example illustrated I have shown six spools 32 supporting six cords B arranged equi-distantly around the mandrel, and six heads 56 correspondingly arranged with six spools 53 so that six longitudinal cords B will be laid with the winding of the conductor on the mandrel and six corresponding cords C will be looped with the conductor turns or windings and with the corresponding cord B. It will be under- 120 125 130

stood, however, that any desired number of appropriate parts for laying any desired number of complementary cords B and C may be arranged relatively to the mandrel.

- 5 When the spools are supplied with cords and the spool 7 is supplied with conductor A the ring 12 will be rotated clockwise in plan, (Fig. 4), with all of the cords B hanging downwardly and the free ends of the 10 cords C tied to the free ends of the cords B. As the ring 12 is rotated its guide 8 will cause the conductor A to be wound around the mandrel, first binding the free ends of cords B, C thereto. During rotation of ring 15 12 the cam member 48 will cause the cord guides 42 to rock vertically in timed relation to the laying of the conductor turns around the mandrel in such a way that each time the guide 8 passes a cord B the corresponding 20 guide 42 will be depressed to carry such cord downwardly through the opening 62^a in head 56 when the openings in the ring guide 55 and in the gear 64 register with the opening 62^a, as in Fig. 10. 25 While the guide 42 and its cord B are thus held depressed the teeth of gear 16 will engage the corresponding gear 77 and cause one complete rotation thereof, whereupon the ring guide 55 will be correspondingly 30 rotated once and the spool 53 will be carried bodily around the depressed cord B, thereby carrying the cord C from a position substantially as shown in Fig. 15 to a position substantially as shown in Fig. 16 with the 35 cord C looped around the cord B. When the teeth 16 pass from gear 77 and its disk 78 next engages the surface 14^a of plate 14, said gear will be retained from rotating until its next cycle the cam member 48 will 40 cause the corresponding guide 42 to rise and lift cord B through openings 62^a, etc., and thereby spread the looped cords C and B from the position of Fig. 16 substantially to the position of Fig. 17 and there retain 45 them until the turn of the conductor A is laid on the mandrel and brought to a position between said cords, substantially as illustrated in Fig. 18, so that with the guide 50 8 drawing the turn of the conductor against the mandrel such conductor will engage the adjacent cord C and force it toward the mandrel, as illustrated in Fig. 19. It will be noted that when cord C has been looped around cord B said cord C will have passed 55 over the preceding conductor turn *a*, (Fig. 17), so that when said turn *a* of conductor A has been pulled snug to a position parallel with the other turns of the coil the looped portion *c* of cord C will be snugged between 60 the said conductor turn and the preceding turn, as indicated in Figs. 18 and 19. Similar operations occur for each pair of the cords B and C each time the guide 8 passes said cords at the mandrel, so that the complementary cords B and C are successively 65

laid and looped with respect to the turns of the conductor and with respect to themselves successively during winding of the conductor around the mandrel. It will be noted that the cord C is not wound around conductor A with a complete turn but is looped between each two adjacent turns of the conductor and across the same, and is looped completely around the cord B, whereby the turns of the conductor coil are 70 secured together in spaced relation. After a desired length of coil has been produced the ends of companion cords B, C may be secured in any desired way, such as by knots 75 at D.

In the coil in Figs. 20 and 21 I have illustrated the longitudinal cords as alternating within and without the turns of the conductor, but it will be understood that said cords may all be without or within the conductor, as desired, instead of alternating as illustrated. Where the longitudinal cord is within the conductor the binding cord is looped across the outside of the corresponding conductor turn and looped around the longitudinal cord within the coil, whereas when the longitudinal cord is without the conductor the binding cord is looped over the longitudinal cord and is looped within the conductor, (see Fig. 21). Where it is 80 desired that the longitudinal cord of the coil shall be on the inside of the wire convolutions and the looping cord shall be on the outside of the convolutions the tensions on the cords are adjusted so as to maintain the inner cord (cord B) taut and permit the looping cord (cord C) to bind the wire with a loop. Where it is desired that the longitudinal cord shall lay outside of the wire convolutions the relative tensions on 85 the cords are reversed or so adjusted that they will maintain the looping cord (cord C) taut and the tension on cord B is released so that the cord B will be pulled between the wire convolutions by the looping 90 cord and cord B will then form the loop around the wire convolutions from the inside and the other cord C will be the exterior longitudinal cord. To accomplish the 95 last named results the cord intended to be the longitudinal cord may be placed upon the spool 53 and the cord intended to be the looping cord may be placed upon the spool 32.

In the example illustrated the central 100 mandrel is shown as circular in contour with grooves to receive the inner longitudinal cords, but the mandrel can be triangular or of any desired polygonal shape in cross section according to the contour of the coils desired to be made, and the cords may be located at any place around the circumference or the sides of the coil. While in Fig. 20 I have illustrated a coil of straight 105 formation in a longitudinal direction it will 110

be understood that the coil may be made of sufficient length to be formed into toroidal or annular shape, such as illustrated in my aforesaid application.

5 Having now described my invention what I claim is:

1. A machine of the character described comprising means to wind a conductor to form a coil, means to guide a cord across the 10 winding, and means to loop another cord across turns of the winding around the first named cord and between adjacent turns to secure the turns in spaced relation.

2. A machine of the character described 15 comprising means to wind a conductor to form a coil, means to guide cords across the winding in spaced relation, and means to loop other cords across successive turns of the conductor and around corresponding 20 first named cords successively in position to be located between successive conductor turns.

3. A machine of the character described 25 comprising means to wind a conductor to form a coil, means to guide a cord across the winding, and means to support a spool of cord and rotate it around the first named cord and across turns of the conductor, said first and second named means maintaining 30 the cords in position to permit the conductor turn to pass therebetween.

4. A machine of the character described 35 comprising means to wind a conductor to form a coil, means to support a cord in operative relation to the winding, means to guide said cord, means to operate the guide to change the position of the cord relatively to the winding, and means to support a spool of cord and rotate the spool bodily 40 around the first named cord, said guide being adapted to separate the cords to permit the winding means to pass therebetween.

5. A machine of the character described 45 comprising means to wind a conductor to form a coil, means to guide a cord across the winding, a rotative disk having an opening for the passage of the first named cord, means to support a spool of cord upon said 50 disk for rotation bodily around the first named cord, and means to rotate said disk and spool to loop its cord around the first named cord in advance of the conductor turn to admit the latter between said cords.

55 6. A machine as set forth in claim 5, in which means are provided to operate said guide to pass the cord through said opening into and from the disk.

7. A machine of the character described 60 comprising means to wind a conductor to form a coil, means to guide a cord across the winding, a rotative disk having an opening for the passage of the first named cord, means to support a spool of cord upon said 65 disk for rotation bodily around the first

named cord, and means to rotate said disk and spool and bring them to rest once for each looping of the second named cord around the first named cord.

8. A machine of the character described 70 comprising means to wind a conductor to form a coil, means to guide a cord across the winding, a rotative disk having an opening for the passage of the first named cord, means to support a spool of cord upon said 75 disk for rotation bodily around the first named cord, means to rotate said disk and spool to loop its cord around the first named cord in advance of the conductor turn to admit the latter between said cords, means to maintain tension on the first named cord, and means carried by said disk to maintain tension on the second named cord between its spool and the winding.

9. A machine of the character described 85 comprising a mandrel, means to support a conductor for rotation around the mandrel, a guide for the conductor guided around the mandrel, means to guide a cord along the mandrel, a spool for a second cord, and 90 means to support said spool for rotation bodily around the first named cord.

10. A machine of the character described comprising a mandrel, means to support a conductor for rotation around the mandrel, 95 a guide for the conductor guided around the mandrel, means to guide a cord along the mandrel, a spool for a second cord, means to support said spool for rotation bodily around the first named cord, and 100 means to cause said cord guiding means to move toward and from the second named cord to place the first named cord in position for rotation of the spool therearound and to separate said cords to admit the conductor therebetween.

11. A machine of the character described 105 comprising a mandrel, means to support a conductor for rotation around the mandrel, a guide for the conductor guided around the mandrel, means to guide a cord along the mandrel, a spool for a second cord, a rotative disk carrying said spool, said disk having an opening to admit the first named cord, guiding means rotatively supporting 110 the disk, and means to rotate said disk and spool to carry the spool around the first named cord and loop the second named cord across a conductor turn.

12. A machine of the character described 120 comprising a mandrel, means to support a conductor for rotation around the mandrel, a guide for the conductor guided around the mandrel, means to guide a cord along the mandrel, a spool for a second cord, a 125 rotative disk carrying said spool, said disk having an opening to admit the first named cord, guiding means rotatively supporting the disk, and means to move said cord guide toward and from the spool relatively to the 130

mandrel to admit the cord into and remove it from said disk.

13. A machine of the character described comprising a mandrel, means to support a conductor for rotation around the mandrel, a guide for the conductor guided around the mandrel, means to guide a cord along the mandrel, a spool for a second cord, a rotative disk carrying said spool, said disk having an opening to admit the first named cord, guiding means rotatively supporting the disk, a ring gear connected with said disk and provided with an opening in its side, pinions in mesh with said gear, and means to rotate said pinions to cause the disk to rotate the spool bodily around the first named cord to loop the second named cord therearound.

14. A machine of the character described comprising means to wind a conductor to form a coil, means to support a cord relatively to the winding, a guide for said cord pivotally supported with relation to the winding, a rotary cam member to move said

guide to operate the cord relatively to the winding, and means to support a spool of cord and rotate it bodily around the first named cord between said guide and the winding.

15. A machine of the character described comprising means to wind a conductor to form a coil, and means to locate a cord along the turns and to loop another cord around the first named cord to locate portions of one of the cords between turns to secure the turns in spaced relation.

16. A machine of the character described comprising means to wind a conductor to form a coil, means to guide a cord across the winding, means to loop another cord across turns of the winding around the first named cord, and means to apply tension to the second named cord sufficient to draw the first named cord between turns of the winding and around the second named cord and to locate the second named cord along the winding.

ALLEN D. CARDWELL.
